GANG VIBRATOR CONSTRUCTION

Arthur William Mall, Chicago, Ill.

Application April 13, 1938, Serial No. 201,761

12 Claims. (Cl. 94—48)

My invention relates to gang vibrator mechanisms and like devices.

My invention relates more particularly to vibrator mechanisms of this type capable of being attached to screed handling machines or other road machinery for use in compacting unset cement or other road building material.

The principal object of the present invention is to provide a gang vibrator capable of being attached to road building or similar machinery.

A further object of the invention is to provide such a mechanism capable of being operated from the road machine and capable of lateral movement upon the same.

A further object of the invention is to provide a plurality of vibrators adapted to be moved about and controlled as a single unit by an operator from a platform on the road building machine to which the mechanism is attached.

A further object of the present invention is to provide a gang vibrator unit including a plurality of vibratory elements adapted to be driven from a single source of power.

A further object of the invention is to provide an improved construction of gang vibrators for operating a plurality of individual vibrator units with a single line shaft and a single source of power mounted upon the end of a screed or other road building machine.

The improved gang vibrator which forms the subject matter of this application may generally consist of a platform movable back and forth on the end of a screed supporting machine or other road building machine. The platform is adapted to support a pivotally mounted super-structure upon which a gasoline engine is positioned. The super-structure may also include a line shaft extending from side to side of the same and provided with a plurality of transmission members for operating individual vibrator units. The super-structure must necessarily be pivotally mounted so that the vibrators can be raised and lowered into the unset concrete when desired by the operator of the finishing machine. With an arrangement like this it will be apparent that the entire slab of the road from one side to the other will be thoroughly vibrated internally with a minimum of power and in a minimum amount of time.

Other objects and advantages will be more apparent from the following description, wherein reference is had to the accompanying four sheets of drawings, upon which

Fig. 1 is a front elevational view of a road

building machine with my improved gang vibrator mounted thereon;

Fig. 2 is a plan view of the same;

Fig. 3 is a vertical sectional view of a portion of the road machine and the gang vibrator taken generally on the lines 3—3 of Fig. 1 with parts broken away in section to more clearly show other parts;

Fig. 4 is a similar vertical sectional view with the carriage for the gang vibrator in a changed position upon the road machine and with the end of the super-structure carrying the individual vibrators tilted upwardly;

Fig. 5 is an enlarged sectional view through the transmission and portion of the flexible shaft of an individual vibrator taken generally on the line 5—5 of Fig. 1;

Fig. 6 is a cross-sectional view through a modified form of transmission showing the use of individual shafts between each vibrator unit; and

Fig. 7 is a side elevational view of the same with the shaft broken in section.

In the embodiment of the invention which I have chosen to illustrate, I have shown a portion of the road building machine 10 supported adjacent its end by the wheels 12 which rest upon the side frames 14 and 16 of the road under construction. A pair of outwardly facing channel members 18 and 20 are mounted upon the frames of the road building machine in parallel relation adjacent the end of the same.

The gang vibrator may be provided with a frame or carriage 22 positioned between the previously described channel members and provided with downwardly extending side wall portions 24 and 26. The rollers 28 and 30 are journaled in the side walls 24 and 26 and engage the channel members 18 and 20. Thus the frame 22 may be rolled back and forth between the positions shown in Figs. 3 and 4 of the drawings and ride in the tracks formed by the channel members 18 and 20.

The frame of the gang vibrator may be provided with a bearing portion 32 which carries a horizontally disposed shaft 34. The super-structure 36 may be formed with the end walls 38 and 40 and be pivotally mounted upon the shaft 34. The structure may be formed with a rear platform 42 to support a source of power such as the gasoline engine 44. The side walls 38 and 40 may extend forward and be rigidly connected to a horizontal channel member 46 which is adapted to extend across the front of the screed to a point adjacent both sides of the same. The channel 46

may support a plurality of transmission housings 48 which are all connected, as will be later described, to a horizontally disposed drive shaft 50. The shaft 50 is provided with a pulley 52 which is 5 in driving engagement with the drive wheel 54 of the engine 44 by means of the V-belt members 56.

A worm wheel 52' may be provided in each of the transmission housings keyed to the shaft 50 10 and in driving relation to a worm wheel 54 vertically disposed in the housing 48 and mounted in the ball bearing member 56. The hub of the worm wheel 54 may have a screw threaded portion 58 mounted in the tapped opening 60 of a hollow stub shaft 62. A flexible shaft 64 provided with a screw threaded tip 66 may engage the lower end of the tapped opening 68 of the shaft 62. A suitable coupler member 70 may connect the flexible shaft housing 72 to a stationary collar 74 in the lower end of the transmission housing 48. A lock nut 76 may hold the same in a fixed position.

The flexible shaft 64 may extend downwardly 25 and be connected in driving relation to an off-balance weight in a vibrator casing 80 suspended below the transmission housing 48. The vibrator which includes the casing and the unbalanced weight may be of the usual type shown and described in my Patent No. 2,073,393 dated March 30 9, 1937. Since that patent gives a complete description of the construction of the same, further details will not be given herein. It is sufficient to state that the lower end of the flexible shaft is in driving engagement with an offset weight 35 mounted in suitable bearings in the upper and lower end of the shell of the housing of the vibrator.

With the apparatus thus described, it will be 40 apparent that a single source of power such as the engine 44 may drive the line shaft 50 and impart vibratory motion to a plurality of vibrator units 80. Because of the fact that it is necessary to raise and lower the vibrators into and out of the unset concrete, the super-structure which 45 supports the engine and the gang of vibrators, has been pivotally mounted upon the support shaft 34 in the frame of the unit. It will also be obvious that the entire gang vibrator may be 50 moved back and forth between the parallel rails 18 and 30 upon the rollers 28 and 20. In order 55 to swing the vibrators about as indicated by the dotted line in Fig. 3, it is only necessary to start rocking the super-structure upon the supporting shaft 32.

In Figs. 6 and 7, I have shown a modified form 60 of construction wherein I employ a plurality of individual shaft members 63 connected to suitable driving means in the transmission housings 48a. The housings may be supported by a hanger mounting 65 secured by suitable bolt members 67 to the front channel member 46. It will be noted that I have provided elongated bolt holes 69 in the channel members 46 so that the exact 65 location of the vibrator unit may be shifted sideways some distance, if desired.

The transmission housing 48a may be provided 70 with a pair of splined drive units 71 and 72 mounted in suitable ballbearing mountings 73 and 75 in side chambers 71 and 79 of the transmission housing. I provide a spiral bevel gear 81 securely fastened to the splined driving members 72 and 71. The spiral bevel gear may mesh with a similarly formed pinion 83 provided with a stub shaft 85 mounted in a pair of ballbearing mem-

bers 87 and 89 in a downwardly disposed portion 91 of the transmission housing.

A collar member 93 may be screw-threadedly secured in the lower end of the housing 91, being held in position by a lock nut 95. The lower end 5 of the collar 93 is screw-threaded and adapted to engage in a tapped opening 99 in the flexible shaft collar 10 similar to that previously described. In a similar manner the flexible shaft 10 64 may have its tip 66 engage in a tubular stub 10 shaft 62 that is screw-threadedly connected to the portion 58 of the stub shaft 85.

It will be noted that the splined driving members 71 and 72 are securely connected together by the extension 71' which provides in the transmission housing in effect a pair of oppositely directed splined driving means. Suitable collars 103 and 105 may be secured to the stub shafts 63 and enclose the open ends of the transmission housing. Suitable dust eliminators and washers 20 may be provided to effectively seal the opening so that no dirt or dust may enter the transmission housing 48a.

With the above construction, it will be seen 25 that the individual vibrators and transmission housings may be shifted to the right or to the left and by the use of the elongated slots 69 in the supporting channel 46, and the comparatively long splined driving units 71 and 72, that a considerable movement of the transmission housings one way or another may be made without 30 in any way disturbing the efficient drive from the source of power to the vibrators.

In the form which I have illustrated, I have 35 provided a pulley 52 on one of the stub shafts 35 which is adapted to be driven at approximately 2300 R. P. M. With a 3 to 1 ratio between the bevel gear 81 and the pinion 83, it will thus be seen that the vibrator attains a speed of approximately 7000 R. P. M.

From the above and foregoing description, it 40 will be apparent to those skilled in the art that changes and modifications may be made in the exact details shown, and I do not wish to be limited in any particular; rather what I desire 45 to secure and protect by Letters Patent of the United States is:

1. Apparatus of the class described adapted to be mounted upon a road building machine, including a pair of spaced parallel channel members 50 mounted on said road building machine, a truck, a frame mounted for back and forth movement between said channel members, a second frame pivotally mounted adjacent one end of said truck, an engine mounted upon said second 55 frame, a horizontal driveshaft mounted at an opposite side of said frame, said driveshaft and engine connected together in driving relation, a plurality of bevel gears on said line shaft, and a plurality of vibrator units suspended below said 60 gear housings in driving connection with said bevel gears.

2. Apparatus of the class described adapted to be mounted upon a road building machine, including a pair of spaced parallel channel members 65 mounted on said road building machine, a truck, a frame mounted for back and forth movement between said channel members, a second frame pivotally mounted adjacent one end of said truck, an engine mounted upon said second 70 frame, a horizontal driveshaft mounted at an opposite side of said frame, said driveshaft and engine connected together in driving relation, a plurality of bevel gears on said line shaft, and a plurality of vibrator units suspended below said 75

gear housings in driving connection with said bevel gears, each of said vibrator units including a flexible shaft, a tubular casing and an unbalanced weight mounted in said casing and driven by said motor through said flexible shaft.

3. Apparatus of the class described capable of being supported upon a road building machine, including a pair of spaced parallel channel members disposed on said road building machine, a truck mounted for back and forth movement between said channel members, a pivotally mounted frame carried by said truck, an engine disposed upon one side of said frame, a plurality of transmission housings disposed upon another part of said frame, stub shafts in driving connection with all of said transmissions, and a plurality of vertically suspended vibrator units driven by said engine through all of said stub shafts and said transmissions.

20 4. An apparatus of the class described comprising a frame, a source of power means mounted thereon, a plurality of transmission housings spaced from each other and mounted on the frame, vibrator units extending from said housings, a shaft journalled in said housings and adapted to be rotated by said power means, and means for adjusting the transmission housings and vibrator units longitudinally of said shaft.

5. A highway vibrating apparatus for compacting concrete comprising a frame, a source of power means mounted thereon, a plurality of transmission housings spaced from each other and mounted on the frame, vibrator units extending from said housings, a shaft member journalled in said housings and adapted to be rotated as a single drive shaft by said power means, said shaft member comprising a plurality of separate sections operatively connected together within the transmission housings, said 35 vibrator units being driven by said shaft member, and means for adjusting the transmission housings and vibrator units longitudinally of said shaft member.

6. A highway vibrating apparatus for compacting concrete comprising a frame, a source of power means mounted thereon, a plurality of transmission housings spaced from each other and mounted on the frame, vibrator members extending from said housings, a shaft member journalled in said housings driven by said power means and operatively connected to said vibrator members, said shaft member comprising a plurality of sections, certain of said sections having openings therein and adapted to slidably receive the corresponding adjacent sections, whereby adjustment of the transmission housings and vibrator members longitudinally of the shaft member may be obtained without interfering with the operation of said shaft member.

60 7. An apparatus for compacting concrete adapted to be mounted upon a road working machine comprising a frame mounted on the road working machine transversely of the roadway, a plurality of vibrating members mounted on the frame and adapted to internally vibrate the concrete, a single drive shaft for operating all of said vibratory members, said drive shaft carried

by the frame and driven by the power means, means for adjusting each vibratory member longitudinally of the drive shaft and independently of the other vibratory members.

8. A vibrating apparatus for compacting concrete in highway construction, comprising a frame, a source of power means mounted thereon, a plurality of transmission housings spaced from each other and mounted on the frame, vibratory members extending from said housings, a shaft member journalled in said housings, driven by said power means and operatively connected to said vibrating members, said shaft member comprising a plurality of sections, certain of said sections having openings and being disposed interiorly of the transmission housings, said sections with openings being adapted to slidably receive corresponding adjacent shaft sections, whereby adjustment of the transmission housings and vibratory members longitudinally of the shaft member may be obtained without interfering with the operation of said shaft member.

9. A vibrating device for compacting concrete in road construction comprising a frame having supporting members adapted to ride upon the forms containing the concrete, a carriage member movably mounted on the frame, a second carriage member pivotally secured to the first carriage member, a plurality of vibratory units supported by the second carriage member, said vibratory units capable of being raised or lowered relative to the concrete by moving the second carriage member about its pivotal connection with the first carriage member, and said vibratory units being capable of horizontal adjustment relative to the frame by moving the first carriage member relative to the frame.

10. An apparatus as defined by claim 9 wherein the raising and lowering of the vibratory units relative to the concrete is facilitated by means of a counter-balancing inertia weight carried by the second carriage member.

11. An apparatus as defined by claim 9 wherein an inertia weight is mounted on the second carriage member on the side of the pivotal connection opposite the vibratory units, whereby the raising and lowering of the vibratory units relative to the concrete is facilitated.

12. A vibrating device for compacting concrete in road construction comprising a frame having supporting members adapted to ride upon the forms containing the concrete, a carriage member movably mounted on the frame, a second carriage member secured to the first carriage member by means of a pivotal connection located in the intermediate region of the second carriage member, a plurality of vibratory units supported by the second carriage member, said vibratory units capable of being raised or lowered relative to the concrete by moving the second carriage member about its pivotal connection with the first carriage member, and said vibratory units being capable of horizontal adjustment relative to the frame by moving the first carriage member relative to the frame.

ARTHUR WILLIAM MALL.
